TELEPHONE CALL APPARATUS

Jacques Servanton and Jean Marie Consaël,
Paris, FranceApplication April 4, 1934, Serial No. 718,986
In France November 24, 1933

12 Claims. (CL 179—90)

The present invention relates to call apparatus for automatic telephone systems, of the type in which the successive openings and closings of an electric contact send, into the telephone line, several sets of impulses separated by intervals of rest, each set of impulses corresponding to a figure or a letter forming part of the call. In apparatus of this class, the successive openings and closings of the electric contact are obtained by means of a pawl cooperating with bars whose position is adjustable, these bars being equal in number to the characters of the call indication; each bar comprises several sections which are toothed in a different manner, and the whole set of bars is movable transversely with reference to the said pawl.

The invention has for its object a call apparatus for automatic telephone systems, which is chiefly characterized by the fact that it comprises a pawl-carrying slide adapted for disposition opposite sets of bars which are adjustable in position and comprise elements or sections whose outline depends upon the character represented by each of said elements; the pawl or pawls carried by the said slide cooperate successively with such elements in order to effect the successive openings and closings of an electric contact.

According to the invention, the apparatus comprises two independent sets of bars which permit composing two call indications, a pawl mounted on the pawl-carrying slide being employed for each of these two sets.

Further characteristics will be specified in the following description.

In the accompanying drawings, which are given solely by way of example:

Fig. 1 is a perspective view of an apparatus constructed in conformity to the invention.

Fig. 2 is a section, on the line 2—2 of Fig. 4, of the internal mechanism of the apparatus.

Fig. 3 is a plan view of this mechanism.

Fig. 4 is a view of one end of the apparatus, with partial removal of a side-plate.

Fig. 5 is a view of the other end of the apparatus.

Fig. 6 represents the arrangement of the electrical connections of the apparatus.

Fig. 7 is a section, on the line 7—7 of Fig. 9 and on a larger scale, of a detail part of the pawl-carrying slide.

Fig. 8 is a corresponding plan view of said slide.

Fig. 9 is a section on the line 9—9 of Fig. 7.

Fig. 10 is a detail view showing, in elevation, a

device for adjusting the rack of the pawl-carrying slide.

Fig. 11 is a view, similar to Fig. 8, of a modification.

Fig. 12 is a view in side elevation, of a device 5 for holding the elements of the call indication in the desired position during the movements of the pawl-carrying slide.

Fig. 13 is a perspective view, on a very large scale, of a pawl pertaining to the slide, with a 10 device for guiding the said pawl.

Fig. 14 is a view, in side elevation of a modification of the apparatus represented in Figs. 2 to 5.

Fig. 15 is a view, similar to Fig. 14 of another 15 modification.

Fig. 16 represents, in perspective, another example of execution of the call apparatus according to the invention.

In the example of execution represented in Figs. 1 to 5, the apparatus comprises bars 1, equal in number to the characters of the call indication (seven in the example represented), which are parallel with one another and are mounted in such manner that they may be moved lengthwise. 25 Thus each of the bars 1 is slidable on a guide 2 secured at each end to two respective plates 3 which are mounted on the cross-pieces 4 of two side-plates 5 and 6 carrying the whole of the mechanism. 30

Each of the bars 1 is provided, on its lower face, with elements or sections 7, each representing a different character which is indicated on the upper face of the bar. According to the position of this latter, the character corresponding 35 to this position will appear in an opening 8 formed in the upper wall of a case 9 containing the whole apparatus.

In the example shown in Fig. 2, the elements 7 have a smooth surface, the length of which varies 40 according to the characters which they represent (this length being counted transversely with reference to the bar). A lever 10 is secured to each bar 1 in order to slide this latter and to bring a chosen element 7 upon a given transverse line 45 X—X. The said levers traverse the upper wall of the case 9 through a slot 11 formed in said wall. The characters corresponding to each position of the bar 1 and lever 10 for which a given element 7 is located on the line X—X are inscribed upon the upper wall of the case 9 along the slot 11. 50

A suitable device serves to hold the bar 1 exactly in the position in which one of its elements 7 is located on the line X—X. In the example 55

represented in Figs. 7 and 9, this device comprises a ball 12 situated in a recess in the wall of the hollow bar 1 and held by a spring strip 13 against the guide 2. The wall of this guide is provided with recesses 14, which have the same spacing as the elements 1 of each bar, and in which the ball 12 is successively engaged during the sliding of the bar 1.

The aforesaid arrangement of the bars 1 thus permits to bring upon the transverse line X—X the element 1 of each bar which corresponds to a given character in the call indication, and hence this indication may be composed once for all; the call signal can be sent into the telephone line as many times as may be necessary, by using an automatic mechanism (to be further described) which may be caused to traverse all said bars along the line X—X, as many times as may be desired, to induce signal impulses.

In the example represented in Figs. 1 to 5, and in the corresponding detail views, the apparatus is further provided with a second device comprising elements 1 which form call indications and may be traversed by a suitable mechanism in order to send into the telephone line the corresponding call signals. This second device comprises a drum 15 whose axis is parallel with the contact line X—X, and which carries at the periphery longitudinal bars 16, each of which represents a determined call indication. On the outer edge of each bar 16 are formed elements 1, whose number corresponds to that of the characters of the call indication represented by the corresponding bar, the length of each element being the one which corresponds to that of the sign which it represents.

The shaft 17 of the drum is journaled in the end-plates 5—6 of the frame, and on said shaft is mounted a gear wheel 18 whose rotation is effected, from a shaft 19, by means of reduction gearing 20 (Figs. 3 and 4). The shaft 19 is threaded, and carries a nut 22 engaging in a longitudinal slot 23 of the case (Fig. 1). This shaft may be rotated either by a hand-crank 21 (Fig. 1) or by operating the nut 22 which is, in this case, provided with a knob. A pointer 24 is secured to the nut 22, and thus, under the effect of the rotation of the shaft 19, this pointer will move along the slot 23 above a table situated adjacent the said slot. This table carries the call indications represented by the bars 16 of the drum 15, or preferably, the names of the subscribers corresponding to such call indications. The speed reduction of the gearing 20 is so selected that when a bar 16 comes under the contact line X—X, the pointer 24 shows the name of the subscriber corresponding to the call indication represented by the said bar.

Obviously, the aforesaid reading device may be replaced by any equivalent device, and for instance by a drum set in rotation by the shaft 19 and mounted under an opening in the case 9, the subscribers' names or the call indications being inscribed upon the surface of said drum.

The holding of the drum 15 in each of its positions for which a bar 16 is situated under the contact line X—X, is assured by a roller 25 (Fig. 5) which is mounted on a spring strip 26 adjustable in position, and which is in contact with the teeth of the gear wheel 18.

A single mechanism is employed for traversing the bars 1 or one of the bars 16 of the drum 15, at will. This device essentially consists of a contact slide 27 moving in either direction along the line X—X. For this purpose, the slide 27 may be

mounted on a shaft 28 by any suitable means in order that the rotation of this shaft cause the displacement of the slide. For example, the shaft 28 may be threaded, and the slide 27 screwed to this shaft.

In the example shown in Figs. 2, and 7 to 9, the shaft 28 traverses the slide 27 and is provided with a helical groove 29 of semicircular section in which are engaged one or more balls 30 (two in the example represented) which are contained in bored recesses in the slide 27. The said slide is further slidable on a guide bar 31, parallel to the shaft 28.

The shaft 28 of the contact slide is connected, by a set of gearing 32, to a toothed sector 33, secured, as to rotation, to a hand-crank 34 for displacing the slide 27 from right to left (Fig. 2), that is, for effecting the inoperative stroke. A spring 35, attached at one end to the axle 36 which is common to the sector 33 and the crank 34, and at the other end to the frame 51, assures the return of the slide to its idle position (shown in Fig. 2), and thus causes it to effect its operative stroke or its return stroke.

A governor 37, of any suitable type, is connected with the shaft 28 of the slide by means of gearing 38 and a ratchet wheel 39 cooperating with a pawl 40 mounted on a disc 41 adapted to rotate together with the shaft 28. This connection is carried out in such way that the shaft 28 will only rotate the governor 37 during the operative stroke of the slide 27. Thus during the return stroke, the slide 27 will move at a determined uniform speed in order that the sending of the impulses of current into the telephone line will be effected at the proper rate; on the contrary, the inoperative stroke of the slide may be effected very rapidly by turning the crank 34.

The slide 27 carries the contact-pieces and other devices for the opening and closing of the electric circuit in order to send current impulses into the telephone line. These devices comprise (Figs. 6 to 8), a cam 42, preferably of insulating material, keyed to an axle 43 situated on the slide 27. To the said axle is also keyed a pinion 44 forming part of a set of reduction gearing 45 cooperating with a rack 46, parallel to the shaft 28. Thus the movement of the slide along this shaft effects the rotation of the cam 42 at a speed proportional to the speed of movement of the said slide, the ratio of these speeds being determined by the ratio of the gearing 45.

Suitable means are provided for effecting a first adjustment of the angular position of the cam 42 with reference to the position of the slide 27 on the shaft 28. In the example represented in Fig. 10, the rack 46 passes freely through the end-plates 5—6 of the frame, in which plates it is slidable, and it carries a projection 47 into which is screwed a regulating screw 48 passing through the end-plate 5. A spring 49, subject to compression, is in contact at one end with this end-plate and at the other end with the projection 47.

The slide 27 further carries two pairs of elastic contact members 50, 51, which are acted upon by the cam 42 during its rotation. One of these pairs of contact members cooperates with the bars 1, and the other with the bars 16 of the drum 15. Each pair of contact members consists of two spring strips 50 and 51 which are suitably insulated and are secured at one end to the slide 27. These two strips are provided with hooks 52, or with other suitable parts, for attaching the electric wires making the connection. The strip 50

preferably comprises a bent part 53 which is in contact with the cam 42. The second strip 51 is bent around at its outer end, being in contact with the said strip 50, and thus, due to the elasticity of the strip 51, the bent strip 50 tends to be separated from the cam 42 (as shown in Fig. 2) and at the lower part of the slide (Fig. 7).

A pawl 54 is pivoted at 55 to the slide 27 in such way as to oscillate in a vertical plane passing through the line X—X. The said pawl carries a lateral arm or journal 56, of insulating material, which bears against the strip 51 when the pawl 54 turns in the direction of the arrow f^1 (Fig. 7). The pointed end of the pawl 54, which makes contact with the elements 7 of the bars 1 (or of the drum 15 in the case of a lower pawl), is rounded on one side according to ab in such manner that during the movement of the slide 27 in the direction of the arrow F (inoperative stroke) the strip 50 will remain separated from the cam 42, even during the movement of the pawl against the elements 7. On the other hand, the outer end of the pawl is beveled at c and d on both of its lateral faces and thus any improper operation of the bars 1 or of the drum 15, when the pawl 54 is adjacent one of these bars, or adjacent the drum 15, will lower the said pawl by a rotation on its pivoting axis 55, thus avoiding all damage to the parts in contact.

In order to make use of either of the pairs of contact members 50—51, according as it is desired to employ the call indications located on the drum 15, or those which consist of the bars 1, the apparatus is provided with a reversing device 57 (Figs. 1 and 6) which is mounted in the electric circuit for inserting in the circuit, at will, either of the two pairs of contact-pieces 50—51. This reversing device may be replaced by any other equivalent device, for instance an arrangement of two plug contacts.

The apparatus is further provided with a device of the usual kind for short-circuiting the listening devices which are connected at 58. This device comprises contact-pieces mounted on conducting spring strips 59 which are suitably insulated. One of these strips 59 carries a stud 60, in contact with a lever 61 upon which the sector 33 is caused to bear, against the action of a spring 64, when the hand-crank 34 is in the idle position (Fig. 4).

On the other hand, a disappearing stop 62 (Fig. 1) is employed in order to limit the movement of the slide 27 in the case in which it is simply necessary to traverse the first bars 1 on the right-hand side. The said stop 62 is connected with a controlling key 63 extending above the upper part of the case 9.

The operation of the aforesaid apparatus is as follows.

With the apparatus in the idle position, as represented in Figs. 2 and 3, the chosen telephone call indication is composed by moving the bars 1 so that the lever 10 of each bar will be brought before the corresponding character, which also appears in the opening 8, the reversing device 57 is placed in the position corresponding to the placing of the bars 1 in service. The call number or indication being thus composed, the operator presses upon the crank 34 in order to turn it in the direction of the arrow f^2 (Fig. 4), and this has the effect of displacing the slide 27 from right to left (arrow F, as shown in Figure 7, and in Figs. 2 and 3). This displacement is very rapid, since the pawl slides upon the ratchet wheel 39, and thus the governor 37 is not actuated. The resistance

offered to such displacements is reduced to the friction; as the end of each pawl 54 is rounded at $a-b$, these pawls disappear by pivoting in the contrary direction to the arrow f^1 (Figs. 7) when they move before the elements 7 of the bars 1 and of the drum 15, and this reduces the friction and the wear.

The pawls 54 being thus moved aside, the spring strips 50 are separated from the cam 42, and hence the rotation of this latter will have no action upon the contact-pieces 50—51.

The slide 27 being at the end of its left-hand stroke, the operator releases the crank 34, and as it is then returned by the spring 35, it assumes the idle position. In this return movement, the shaft 28 rotates in the contrary direction to the preceding and thus causes the displacement of the slide 27 from left to right. On the other hand, this shaft, by means of the pawl 40, moves the ratchet wheel 39 and hence the governor 37, so that the return movement of the slide 27 is effected at a determined uniform speed.

During this return movement, the upper pawl 54 makes contact successively with the elements 7 of the bars 1 situated along the line X—X. When the pawl meets with one of these elements, it will pivot in the direction of the arrow f^1 (Figure 7, and the journal 56 makes contact with the spring strip 51, thus permitting the two strips 50 and 51 to come near the cam 42. The device consisting of the pawl 54 and the said strips remains in this position as long as the pawl is in contact with the element 7.

The cam 42, which is caused to rotate, during the displacement of the slide 27, by the rack 46 and the gearing 44—45, will thus periodically raise the strip 50, thus causing openings and closings of the contact at 50—51. The number of openings and closings thus effected, and hence the number of impulses sent into the telephone line, will be evidently proportional to the length of the element 7 against which the pawl 54 is caused to bear. With the form of cam represented in the drawings, during the movement of the pawl 54 under an element 7 which occupies the whole width of the bar 1, said cam will make five complete revolutions, and hence will effect ten breaks of the current.

When the pawl 54 leaves the element 7, it returns to the idle position under the action of the spring strip 51 which separates the strip 50 from the cam 42, and thus the rotation of said cam causes no break of the circuit, until the pawl 54 meets the element 7 of the next bar. As the pawl 54 thus traverses all the bars 1 in succession, the impulses of current which correspond to the characters of the call indication, preliminarily composed, are sent successively into the telephone line.

It should be observed that during the whole of the displacement of the slide 27 in one or the other direction, the listening devices are short-circuited. In fact, when the operating crank 34 is lowered, the lever 61, urged by the compression spring 64, separates from the stud 60, and the spring strips 59 make contact with one another. It is only at the end of the return stroke of the slide 27, that the sector 33 bears upon the lever 61, thus separating the strips 59.

In the case in which the call indication which it is desired to send into the telephone line is one of those represented by the bars 16 of the drum 15, the operator turns the reversing device 57 in order to bring it into the corresponding position (represented in the diagram, Fig. 6). 75

He turns the shaft 19 by means of the crank 21 in order to bring the pointer adjacent the name of the subscriber which is to be called, and this has at the same time the effect of turning the drum 15 and of bringing, next the lower pawl 54 of the slide 27, the bar 16 corresponding to the desired call indication. In order to send out the call, it is simply necessary to act, as before, upon the lever 34.

10 The call apparatus above described may comprise various accessory arrangements. Thus it is possible to provide an arrangement of the parts such that this will permit to compose the call indication and to effect the idle stroke or inoperative stroke of the slide 27, but preventing the return stroke of the said slide, and consequently the sending of the call indication, before the listening devices have been removed from their hooks. For example, the disc 39 (Fig. 2), 15 which rotates together with the driving shaft of the slide 27, comprises at its periphery a set of teeth 65 adapted to be engaged by the end of a lever 66 connected with the hook or like support (not shown) of the listening devices. A spring 20 (not shown) tends to separate the lever 66 from the teeth 65. The position of this lever and the inclination of the teeth are such that they permit the rotation of the disc 39 when the slide 27 moves from right to left and they counteract the movement in the other direction. Thus the return of the slide will not take place except when the listening devices are unhooked, as the lever 66 is then separated from the teeth 65 by the reaction spring, and thus releases the disc 39.

30 In Fig. 11 is represented a modification of the arrangement for moving the slide 27. In this example of execution, the shaft 28 of the slide has a longitudinal slot 67 in which is engaged the end of a screw 68, screwed into a collar 69 secured to a bevel gear wheel 70. This wheel 70 engages a second gear wheel 71 keyed to a shaft 72 which is mounted on the slide and to which is also keyed one of the wheels of the set of gearing 45.

40 It is observed that the movement of rotation imparted to the shaft 28 by the lever 34 is transmitted to the bevel wheel 70 and thence to the gearing 45, thus effecting the displacement of this set of gearing, and hence, of the slide carrying this latter, along the rack 44.

45 A device may be provided for automatically assuring the locking of the bars 1 and of the drum 15 when the contact slide 27 is displaced in either direction, and for releasing the said bars 50 and drum when the slide has assumed the idle position. Such a device is shown in Fig. 12. This device comprises two levers 73 and 74, pivoted at 75 and 76; their free ends, forming hooks, are adapted for engagement between two bars 60 16 of the drum 15, for the lever 74, and between two elements 7 of the bars 1, for the lever 73. This last-mentioned lever has a sufficient length, measured on its pivot axis, in order to hold at the same time all of the bars 1. The levers 73 65 and 74 are connected by links 77 and a rod 78 with a lever 61 actuated by the sector 33. It will thus be readily understood that when the slide 27 is in the idle position (the sector 33 then having the position represented in Fig. 12), the bars 70 1 and the drum 15 are released. When the operator acts upon the operating lever 34 in order to displace the slide 27, the sector 33 becomes separated from the lever 61 which then moves in the direction of the arrow f^3 under the action 75 of the compression spring 64 and effects the simul-

taneous locking of the bars 1 and the drum 15. This prevents all improper operation during the transmission of the call indication.

However, if the apparatus is not provided with a device for locking the bars 1 and the drum 15, it is possible to employ, for each of the pawls 54, a guiding member 79 mounted on the slide 27 (Fig. 13) and provided with an elongated opening through which the end of the pawl 54 extends. Due to this arrangement, an improper 10 operation of the bars 1 or of the drum 15 will not cause the pawls 54 to be torn off.

The drum 15 may be replaced by any other suitable support for the bars 16. In the example represented in Fig. 14, this support consists of 15 a plate 80 upon which the bars 16 are maintained by any suitable means. This plate 80 has upon its lower face a transverse rack 81 cooperating with a pinion 82 keyed to the shaft 17.

The drum 15 may also be replaced by a second 20 set of bars 83 (Fig. 15) constructed in a manner analogous to the first-mentioned set of bars 1, and also permitting to compose a call indication. Each of the bars 83 is also provided with an operating lever 84. The use of two sets 25 of bars is particularly advantageous, as it provides for the preliminary composing of two call indications, and for the transmission, at will, of one or the other of these indications, without requiring to perform any other accessory operation than the handling of the reversing device 51.

30 Fig. 16 represents a modified execution of the apparatus according to the invention. In this modification, the slide 107 comprises a projection 85 which will bear against the upper face 35 of a fixed guiding bar 86 parallel to the shaft 108 of the said slide. This slide is also provided with a second projection 87 which will bear against the lower face of the guide bar 86 when the slide turns upon the shaft 108 in the direction of the arrow f^4 .

40 On the slide 107 is pivotally mounted at 88 a pawl 89, which is extended, on the other side of its pivoting axle, by an arm 90 carrying at its outer end a roller 91. Said roller rests upon a 45 strip 92, parallel to the shaft 108 and pivotally mounted on an axle 93 having the same direction as the said shaft. The strip 92 rests upon a stud 94 mounted on the end of a spring strip 95 which is pivoted at the other end to a fixed axle 96. The strip 95 carries a contact-piece 97 cooperating with a like piece 98 mounted on a second spring strip 99 which is secured at its other end at 100.

45 Bars 101, equal in number to the characters of the call indications, are slidable on guides 102 and are provided with toothed elements or sections 103, which are parallel to the shaft 108 of the slide 107 and will cooperate with the pawl 89. The number of teeth of each element or section depends upon the character which it represents. 60

50 The shaft 108 is connected, in the same manner as in the example shown in Figs. 2 and 3, with a lever 104 whose stroke can be limited by a disappearing stop 105. A spring 106 assures the return of the parts to the idle position. A governor 65 109 is connected with the shaft 108 by means of a device consisting of a ratchet wheel 110 and a pawl 111, so arranged that the said governor will not be operated except on the return stroke of the contact slide. On the other hand, the return movement of the slide 107 may be prevented, as above indicated, by a lever 112 engaging the teeth 113 of a wheel 114 which is keyed to the shaft 108, said lever being secured to the support 115 of the listening devices and subjected to 70 75

the action of a spring 116 which tends to separate it from said wheel.

The apparatus further comprises a device for short-circuiting the listening devices analogous to the one above described and controlled by a cam 117 which rotates together with the operating lever 104.

The operation of the contact device of the apparatus shown in Fig. 16 is as follows. During the setting stroke or inoperative stroke of the slide 107, the shaft 108 turns in the direction of the arrow f^4 and thus rotates the said slide until the projection 87 makes contact with the lower face of the guide bar 86. Due to this pivoting of the slide, the pawl 89 is entirely released from the bars 101, and the roller 91 has now left the strip 92. The slide 107 will thus move, while remaining in this angular position, as far as the end of the stroke (to the left of Fig. 16) and thus the contact at 97-98 will not be affected by this displacement of the slide, and will remain closed.

When the listening devices are unhooked, the lever 112 rises and thus releases the gear wheel 113, which permits the return of the various parts 25 to their idle position under the action of the spring 106.

At the beginning of the return movement, the shaft 108 turns in the contrary direction to the arrow f^4 , and it thus pivots the slide 107 in the same direction until the projection 85 makes contact with the upper face of the guide bar 86. After this time, the rotation of the shaft 108 causes the slide 107 to move from left to right, and the pawl 89 makes contact successively with the teeth 35 103 of the bars 101. Each time that it passes before a tooth, the pawl 89 descends, and the roller 91 is also lowered, thus pivoting the strip 92 and breaking the contact at 97-98.

Having now described our invention what we claim as new and desire to secure by Letters Patent is:

1. In an automatic signal apparatus, two series of call mechanisms, one series having signals composed at the moment of use, the other having call signals prepared in advance, all of the signals being composed along parallel lines, a single slide mounted for reciprocal movement parallel to the signals and carrying two pawls, one pawl acting on the signals prepared in advance and the other pawl acting on the signals composed at the moment of use, means for causing unrestricted movement of the slide in one direction and automatic means for causing controlled movement of the slide at constant speed in the opposite direction.

2. In an automatic signal apparatus, two series of call mechanisms, one series having signals composed at the moment of use, the other having call signals prepared in advance, all of the signals being composed along parallel lines, a single slide mounted for reciprocal movement parallel to the signals and carrying two pawls, one pawl acting on the signals prepared in advance and the other pawl acting on the signals composed at the moment of use, means for causing unrestricted movement of the slide in one direction and automatic means for causing controlled movement of the slide at constant speed in the opposite direction and means for selectively energizing the call mechanisms.

3. In an automatic signal apparatus, a set of transversely movable longitudinally spaced bars, pawl actuating signal elements carried by the bars, a drum rotatably mounted in longitudinal alignment with the set of bars, a series of elongated circumferentially spaced strips carried on the surface of the drum and each formed with different predetermined pawl actuating signal elements, a slide mounted for longitudinal reciprocation between the set of bars and the drum, a pair of contact breakers carried by the slide, a pair of pawls also carried by the slide for coacting with the contact breakers and respectively with the pawl actuating signal elements on the bars and on the strips.

4. In an automatic signal apparatus, a set of transversely movable longitudinally spaced bars, pawl actuating signal elements carried by the bars, a drum rotatably mounted in longitudinal alignment with the set of bars, a series of elongated circumferentially spaced strips carried on the surface of the drum and each formed with different predetermined pawl actuating signal elements, a slide mounted for longitudinal reciprocation between the set of bars and the drum, a pair of contact breakers carried by the slide, a pair of pawls also carried by the slide for coacting with the contact breakers and respectively with the pawl actuating signal elements on the bars and on the strips.

5. In an automatic signal apparatus, a frame, a shaft journaled in the frame, a set of bars equidistant from the shaft, spaced longitudinally of the shaft and mounted for longitudinal reciprocation in a direction transverse to the axis of the shaft, a series of pawl actuating signal elements carried by each bar, a drum journaled in the frame with its axis parallel to the axis of the shaft, a series of elongated circumferentially spaced strips on the surface of the drum and each formed with different predetermined pawl actuating signal elements, a slide mounted on the shaft for longitudinal reciprocation between the sets of bars and the drum, a pair of contact breakers carried by the slide, a pair of pawls carried by the slide for coacting with the contact breakers and, respectively, with the pawl actuating signal elements on the bars and on the strips.

6. In an automatic signal apparatus, a frame, a shaft journaled in the frame, a set of bars equidistant from the shaft, spaced longitudinally of the shaft and mounted for longitudinal reciprocation in a direction transverse to the axis of the shaft, a series of pawl actuating signal elements carried by each bar, a drum journaled in the frame with its axis parallel to the axis of the shaft, a series of elongated circumferentially spaced strips on the surface of the drum and each formed with different predetermined pawl actuating signal elements, a slide mounted on the shaft for longitudinal reciprocation between the sets of bars and the drum, a pair of contact breakers carried by the slide, a pair of pawls carried by the slide for coacting with the contact breakers and, respectively, with the pawl actuating signal elements on the bars and on the strips.

7. In an automatic signal apparatus, a frame, a shaft journaled in the frame, a set of bars equidistant from the shaft, spaced longitudinally of the shaft and mounted for longitudinal reciprocation in a direction transverse to the axis of the shaft, a series of pawl actuating signal elements carried by each bar, a drum journaled in the frame with its axis parallel to the axis of the shaft, a series of elongated circumferentially spaced strips on the surface of the drum and each formed with different predetermined pawl actuating signal elements, a slide mounted on the shaft for longitudinal reciprocation between the sets of bars and the drum, a pair of contact breakers carried by the slide, a pair of pawls carried by the slide for coacting with the contact breakers and, respectively, with the pawl actuating signal elements on the bars and on the strips and means for selectively energizing the contact breakers.

8. In an automatic signal apparatus, two series of call mechanisms one series composed of a plurality of relatively movable bars having spaced pawl actuating signal elements whose outline depends upon the character represented by each element, which elements may be arranged in a predetermined line in different sequences by relative movement of the bars; the other series composed of strips each having a predetermined different series of pawl actuating signal elements constituting a complete signal, said strips being selec-

- 5 tively movable into spaced alignment with the predetermined line of elements on the bars; a slide mounted to reciprocate between the mechanisms; a pair of contact breakers carried by the slide; and a pair of pawls on the slide coacting with the respective contact breakers and respectively with the elements on the bars and strips.
- 10 8. In an automatic signal apparatus; two series of call mechanisms; one series composed of a plurality of relatively movable bars having spaced pawl actuating signal elements whose outline depends upon the character represented by each element, which elements may be arranged in a predetermined line in different sequences by relative movement of the bars; the other series composed of strips each having a predetermined different series of pawl actuating signal elements constituting a complete signal, said strips being 15 selectively movable into spaced alignment with the predetermined line of elements on the bars; a slide mounted to reciprocate between the mechanisms; a pair of contact breakers carried by the slide; a pair of pawls on the slide coacting with 20 the respective contact breakers and respectively with the elements on the bars and strips and means for causing unrestricted movement of the slide in one direction and automatic means for causing controlled movement of the slide at constant speed in the opposite direction.
- 25 9. In an automatic signal apparatus; two series of call mechanisms; one series composed of a plurality of relatively movable bars having spaced pawl actuating signal elements whose outline depends upon the character represented by each element, which elements may be arranged in a predetermined line in different sequences by relative movement of the bars; the other series composed of strips each having a predetermined different series of pawl actuating signal elements constituting a complete signal, said strips being 30 selectively movable into spaced alignment with the predetermined line of elements on the bars; a slide mounted to reciprocate between the mechanisms; a pair of contact breakers carried by the slide; a pair of pawls on the slide coacting with the respective contact breakers and respectively with the elements on the bars and strips; means for causing unrestricted movement of the slide in one direction, automatic means for causing controlled movement of the slide at constant speed in the opposite direction and means for 35 selectively energizing the call mechanisms.
- 35 10. In an automatic signal apparatus, a set of transversely movable longitudinally spaced bars, pawl actuating signal elements carried by the bars, a drum rotatably mounted in longitudinal alignment with the set of bars, a series of elongated circumferentially spaced strips carried on the surface of the drum and each formed with different predetermined pawl actuating signal elements, a slide mounted for longitudinal reciprocation between the bars and the drum and carrying a pair of pawls, a cam mounted for revolute movement between the pawls and a pair of contact breakers adapted to be moved by the pawls into coacting engagement with the cam upon engagement of the pawls with the signal ele- 40 5
